UNITED STATES PATENT OFFICE.

CHARLES E. VERHUNCE, OF CHICAGO, ILLINOIS, ASSIGNOR TO R. WILLIAMSON & CO., OF CHICAGO, ILLINOIS, A CORPORATION OF ILLINOIS.

PORTABLE GAS-LIGHTING OUTFIT.

1,379,372.

Specification of Letters Patent. Patented May 24, 1921.

Application filed January 22, 1918. Serial No. 213,121.

To all whom it may concern:

Be it known that I, CHARLES E. VERHUNCE, a citizen of the United States, and a resident of Chicago, in the county of Cook and State of Illinois, have invented certain new and useful Improvements in Portable Gas-Lighting Outfits, of which the following is a full, clear and exact description.

The invention relates to portable gas lighting outfits.

One object of the invention is to provide an improved portable gas lamp which is adapted for service in a tent or other structure. In lighting outfits of this character, it is desirable to provide a lamp which may be supported over head without danger of burning the tent or structure in which the outfit is installed. To meet this requirement, the invention includes a portable gas lamp which is organized and supported so as to overcome any danger of a conflagration.

In attaining this object, the lamp is provided with one or more supply connections at one side thereof, as distinguished from the usual central combined supply pipe and support. This provision makes it possible to use flexible tubing to supply gas to the lamp and to keep the tubing out of the upward path of the heat or products of combustion from the burner. In conjunction with the side gas connection, a flexible metallic support, such as a chain which is non-inflammable, is utilized to support the lamp in desired position from the ridge pole of the tent or other support of the structure in which the lamp is installed.

A further object of the invention is to provide an improved construction of gas lamp in which there is no flame in the central portion of the lamp, so that there will be a current of air flowing upwardly which serves to quickly cool the products of combustion, the burners being circumferentially disposed within and around the reflector.

Another object of the invention is to provide an improved reflector and support for a portable gas lamp which are slidably connected so that the support may be slipped into the reflector for convenience in packing the outfit. It will be understood that it is the desideratum in lighting outfits of this character to pack the parts in a small area for convenience in transportation.

Lastly, the invention designs to provide a portable gas lamp which is simple in construction and efficient in operation.

The invention consists in the several novel features hereinafter set forth and more particularly defined by claims at the conclusion hereof.

In the drawings: Figure 1 is a perspective showing the improved portable gas lighting outfit in use. Fig. 2 is a plan view of the lamp. Fig. 3 is an inverted plan or bottom view of the lamp. Fig. 4 is a side elevation of the lamp and Fig. 5 is a vertical section.

The improved lighting outfit is illustrated as installed in a hospital tent *a* and comprises a portable gas tank *b* and a flexible tube *c* which is suitably connected to the tank and controlled by a suitable valve as well understood in the art, to supply gas to a portable lamp suspended from the top of the tent or structure.

The improved lamp comprises a conoidal reflector *7*. Around the lower margin of the reflector, there is disposed a hollow ring *8*, to which a metallic nipple *9* is connected by means of a valve *10*, to supply gas to the ring *8* from the flexible tube *c*. Ring *8* is connected to the lower margin of the reflector *7* by slotted lugs or plates *13* and thumb-screws *14*. For convenience in packing and assembling, the tube *c* is detachably connected to the nipple *9* by a coupling *11*. A series of burners *12* extend inwardly and slightly upwardly from the inside of the hollow ring *8* and below the lower margin of the reflector. The reflector is preferably formed of sheet metal and has an opening in its top, the metal being reverted as at *15*, to stiffen the upper portion of the reflector. A hood *16* is slidably mounted in the top of the reflector and comprises a cylindrical metal body *16* which is provided with outwardly extending struck-up tongues *17* which serve as stops upon which the reflector rests and by which it is supported from the hood and a cowl or top-shade *18* which is secured in fixed and spaced relation to the top of the body *16* by lugs *19* which are riveted to the cowl and said body. The body *16* is also provided with outlet openings *20* which are formed by bending tongues *21* inwardly. The products of combustion escape through these openings *20* and the

space between the body 16 and cowl 18. The tongues 21 and cowl 18 serve to deflect the heat laterally so there will be no strong upward draft that will endanger the structure 5 in which the lamp is installed. A metallic chain 22 is secured to an eye 23 which is secured in the cowl 18 and is adapted to be looped around the ridge pole of a tent or any other convenient support and is provided with a hook 24 adapted to pass into the eye 23 to support the lamp in desired overhead position.

In some instances, it is desirable to supply 15 an additional lamp or burner from the supply hose *c*. For example, a small burner to illuminate the entrance to the tent and for this purpose a metallic nipple 25 is secured to the hollow ring 8 diametrically opposite to the nipple 9 and a semi-circular supply pipe is connected to these nipples to conduct 20 gas to nipple 25 from nipple 9. An auxiliary flexible tube section *d* is connected to the nipple 25 by a detachable coupling 26 and this flexible tube is suitably connected 25 to the auxiliary burner *e*. The supply of gas through the tube *d* is controlled by a valve *e'* at the burner *e*. The flexible tubes are supported beneath the ridge-pole by straps 27.

30 In operation, as a result of the arrangement of the burners shown, the flame from the burners will not reach the center of the reflector, thus leaving space for a current of cold air through the center of the reflector 35 which acts quickly upon the products of combustion and causes the latter to be materially cooled before they reach the body 16 of the hood. On reaching the body, the products of combustion and heat will strike 40 the reflecting tongues 21 and the cowl 18 and be deflected laterally to break up any strong draft which might cause ignition of the structure in which the lamp is installed or of the flexible tubing.

45 The invention thus exemplifies a gas burner in which provision is made for a central current of cool air to cool the products of combustion and prevent a strong upward draft to a point above the lamp.

50 Also one in which shadows are avoided.

In a portable lighting outfit, it is desirable that the parts of the lamp should be susceptible of being packed into a small container, and the slidable connection between 55 the body 16 and reflector 7 exemplifies a portable gas lamp by which the hood may be slipped downwardly into the reflector, as indicated by dotted lines in Fig. 5. As a result, this construction can be packed in a 60 cylindrical box or container approximately the height of the reflector, in lieu of the combined effective height of the hood and reflector. The coil of flexible tubing may be disposed in the box around the upper 65 portion of the reflector.

The invention is not to be understood as restricted to the details set forth, since these may be modified within the scope of the appended claims, without departing from the spirit and scope of the invention.

70

Having thus described the invention, what I claim as new and desire to secure by Letters Patent, is:

1. In a portable gas lighting outfit, the combination of a reflector having an open 75 bottom, one or more gas burners adjacent the bottom of the reflector, a gas supplying connection for the burners, and a hood slidably connected to the reflector and adapted to pass into the reflector.

80

2. In a portable gas lighting outfit, the combination of a reflector having an open bottom, one or more gas burners adjacent the bottom of the reflector, a gas supplying connection for the burners, and a hood slidably connected to the reflector and adapted to be folded into the reflector, and comprising a perforated cylindrical body and a cowl.

85

3. In a portable gas lighting outfit, the 90 combination of a reflector having an open bottom, one or more burners adjacent the bottom of the reflector, a gas supplying connection for the burners, disposed at one side of the reflector, a flexible tube connect- 95 ed to said connection, a hood slidably connected to the reflector and adapted to be folded into the reflector, and comprising a cowl, a flexible metallic suspension device connected to said cowl, and supporting stop- 100 means between the hood and the reflector.

100

4. In a portable gas lighting outfit, the combination of a reflector, one or more burners adjacent the bottom of the reflector, a gas supplying connection for the burners, and a hood slidably connected to the reflector and adapted to be folded into the reflector, said hood comprising a hollow body 105 being formed with openings and struck-up tongues.

110

5. In a portable gas lighting outfit, the combination of a reflector, one or more burners adjacent the bottom of the reflector, a gas supplying connection for the burners, and a hood slidably connected to the reflector, said hood comprising a hollow body, 115 formed with openings and struck-up tongues and a cowl secured to the upper end of said body.

115

6. In a portable gas lighting outfit, the combination of an annular conoidal reflector, a plurality of gas burners adjacent the bottom of the reflector, a hollow ring to which the burners are connected, a nipple at 125 one side of the ring, a flexible tube adapted to be connected to said nipple, a hood connected to the reflector, comprising a cowl, and a perforated body, a non-inflammable flexible suspension device for the hood and 130

adapted to support the lamp, and a supporting connection between the reflector and the hood.

7. In a portable gas lighting outfit, the combination of an annular conoidal reflector, a plurality of gas burners adjacent the bottom of the reflector, a hollow ring to which the burners are connected, a nipple at one side of the ring, a flexible tube adapted

to be connected to said nipple, a hood slidably connected to the reflector, comprising a cowl and a perforated body, a non-inflammable flexible suspension device for the hood and adapted to support the lamp, and a supporting connection between the reflector 15 and the hood.

CHARLES E. VERHUNCE.
